HEAT EXCHANGER

Anthony A. Fennell, Homewood, Ill.

Application July 5, 1957, Serial No. 670,029

7 Claims. (Cl. 257—262.15)

The present invention relates to a novel heat exchanger structure, and more particularly to a novel heat exchanger for transferring heat from one stream of fluid to another, which heat exchanger is, for example, especially useful in an industrial furnace as a recuperator.

It has been proposed to provide a heat exchanger including conduit means and a plurality of elements or pins extending through the wall of the conduit means for promoting heat transfer between one fluid within the conduit means and another fluid outside of the conduit means. When such a heat exchanger is used as a recuperator in an industrial furnace or in some other installation where it is subjected to high temperature gases or fluids, there is danger that portions of the pins exposed to the hot gases will be burned.

An important object of the present invention is to provide novel heat exchanger structure of the type contemplated above wherein the pins or similar elements are constructed and arranged so as to reduce any possibility of injury thereto or burning thereof while at the same time promoting efficient operation of the heat exchanger.

A more specific object of the present invention is to provide a novel heat exchanger of the above described type having elements or pins with opposite end portions respectively projecting outwardly of and inwardly of the wall of the conduit means, which pin portions are constructed so as to provide a predetermined ratio between the sizes or areas thereof, and said ratios of pins arranged at different locations being varied in accordance with the temperature environment at such location so as to promote more efficient heat exchange while resisting damage or burning of the pins.

Other objects and advantages of the present invention will become apparent from the following description and the accompanying drawings wherein:

Fig. 1 is an elevational view of a furnace or the like of known construction having a heat exchanger embodying the principles of the present invention associated therewith;

Fig. 2 is an enlarged fragmentary perspective view showing the novel heat exchanger of the present invention disposed in assembled relationship with a flue pipe of a furnace;

Fig. 3 is an enlarged cross sectional view taken generally along the lines 3—3 in Fig. 1;

Fig. 4 is a further enlarged cross sectional view along line 4—4 in Fig. 3;

Fig. 5 is a fragmentary enlarged partial sectional view taken along line 5—5 in Fig. 4;

Fig. 6 is a fragmentary enlarged partial sectional view taken along line 6—6 in Fig. 4; and

Fig. 7 is a fragmentary enlarged partial sectional view taken along line 7—7 in Fig. 4.

Referring now more specifically to the drawings wherein like parts are designated by the same numerals throughout the various figures, a heat exchanger assembly 10 incorporating the features of the present invention is shown mounted in a flue pipe 12 of a furnace 14 of known construction.

As will be understood, the heat exchanger in this installation is adapted to transfer heat from escaping flue gases to another fluid such as air and, in this installation, the air is to be used as combustion air in the furnace. The heat exchanger assembly is provided with an air supply manifold 16 which directs air to conduit means generally designated by the numeral 18 extending into the flue pipe 12, which conduit means has outlet means connected with another manifold 20 which extends to the furnace.

In the embodiment shown for the purpose of illustrating the present invention, the conduit means 18 is provided by a plurality of generally U-shaped pipes 22, 24, 26 and 28. Each of the pipes or tubes 22—28 has an inlet end connected with the manifold 16 and extends transversely into the flue pipe 12 through an opening which is sealed by suitable packing means 30. An outlet leg of each of the U-shaped tubes or pipes extends through a similar opening in the flue pipe 12 that is closed by suitable packing means 22, and each of the outlet legs of the tube is welded or otherwise suitably connected to the outlet manifold 20. In order to promote intimate contact of the flue gases flowing in a stream through the flue pipe 12 with the heat exchanger tubes, each of the tubes is provided with a substantially streamlined transverse cross sectional shape identical to the cross sectional shape of the tube 22 shown in Fig. 4. As shown in Fig. 4, this cross sectional shape has an enlarged upstream or leading marginal or edge portion 34, tapering opposite side portions 36 and 38 and a smaller trailing or downstream marginal or edge portion 40. Pins 42 are spaced longitudinally and transversely of the leading edge portion 34 of each tube and somewhat similar pins 44 and 46 are respectively spaced longitudinally and transversely of the opposite sides and trailing or downstream edge portions of the tubes. These pins serve to increase the heat exchanger area exposed to the fluids and also to reduce or eliminate laminar flow of the gases around the streamlined tube to promote more intimate contact of the gases with the tube and thereby increase the efficiency of the heat exchanger.

It will be appreciated that the temperature of the flue gases approaching the upstream or leading tube 22 of the heat exchanger assembly will frequently be sufficiently high to cause injury or burning of the pins in the absence of proper cooling of the pins. Furthermore, as the gases pass over the heat exchanger the temperature thereof is progressively reduced so that the leading pins 42 will be subjected to higher temperatures than the trailing pins 44 and the pins 44 will be subjected to a higher temperature than the trailing pins 46. Injury or burning of outer ends of the pins may be prevented by correlating the ratio between the sizes or surface areas of outer and inner end portions of the pins and the expected temperatures of the gases flowing over and within the tubes so that heat is conducted from the outer or heated ends of the pins to the inner or cooler ends of the pins and thence to the cooler gases at a rate which is sufficient to prevent overheating of the pins. In accordance with a feature of the present invention, the pins are constructed in this manner so as to avoid injury thereto and at the same time the ratio between the sizes or areas of opposite ends of the pins is changed for pins disposed at spaced locations subjected to different temperatures so as to promote more efficient heat transfer.

As shown in Figs. 4 and 5, the pins 42 at the leading margin of the heat exchanger 2 are formed so that the size or area of outer end portions 48 thereof is relatively

small as compared with the size of area of inner end portions 50 thereof. In other words, in the embodiment shown the outer end portion 48 of the pin has a diameter smaller than the inner end portion 50 so that the inner end portion is effective for transferring heat from the outer end portion and to a relatively cool fluid stream flowing through the tube at a rate which is sufficient, when compared with the rate at which the outer smaller end portion 48 absorbs heat from the flue gases, to prevent overheating of the pin portion 48. As the flue gases pass the pins 42 they are cooled sufficiently so that outer end portions 52 of the pins 44 may be enlarged as compared with the outer end portions 48 of the pins 42 for absorbing heat at about the same rate as the outer pin end portion 48 even though the temperature of the flue gases is lower. Inner portions 54 of the pins 44 are also constructed so as to prevent overheating of the outer end portions 52, but in view of the lower flue gas temperatures at this location the ratio of the inner end portion 54 area to the outer end portion 52 area is less than the corresponding ratio between the areas of the inner and outer end portions of the pins 42. This change in the ratio has been illustrated in the drawings by making the inner and outer end portions of the pins 44 substantially equal in size.

The temperature of the gases passing the pins 42 is further reduced so that outer end portions 56 of the pins 46 are further enlarged as compared with outer end portions of the preceding pins in order to maintain the desired rate of heat transfer. Inner end portions 58 of the pins 46 are also of a size sufficient to prevent overheating of the outer end portions 56 and, in view of the lower temperatures of the flue gases, the inner end portions 58 may, in many cases, be smaller in size or area than the outer end portions 56. In addition to decreasing the ratio between the areas of the inner and outer portions of pins spaced transversely of each tube in the direction of flow of the flue gases, the ratio between the areas of inner and outer pin portions of pins on each of the tubes 24-28 may be decreased with respect to the corresponding ratio of the pins on each preceding tube since the temperature of the flue gas will be reduced as it passes from tube to tube. It is also to be noted that the rate of heat transfer from the outer ends to the inner end portions of the pins will vary for pins spaced along each of the U-shaped tubes from the entering to the outlet ends of the tubes since the air will be heated as it passes through the tubes so that the temperature differential between the air and the pins decreases. Thus, in addition to varying the ratio between the areas of the inner and outer ends of the pins spaced transversely of the tubes and in the direction of flue gas flow, said ratio may also be varied for the pins on each tube and spaced along the tube in the direction of air flow through the tube. More specifically, the pins 42 at the leading marginal portion of a tube are formed in the manner shown and described above so that the ratio between the inner end portion 50 and the outer end portion 48 is smallest for pins adjacent the inlet of the tube and is increased for pins spaced along the tube toward the outlet end thereof. Said ratios for the remaining pins 40 and 46 may similarly be varied. With this arrangement, it will be appreciated that all of the pins may be formed so as to minimize any possibility of injury or burning thereof, and at the same time more rapid and efficient heat transfer in all portions of the heat exchanger assembly is accomplished.

While the preferred embodiment of the present invention has been shown and described herein, it is obvious that many structural details may be changed without departing from the spirit and scope of the appended claims.

The invention is claimed as follows:

1. A heat exchanger comprising tube means for a first fluid stream which enters at a first temperature, said

tube means being disposable in a second fluid stream which approaches a leading portion of the tube means at a second and different temperature, one of said temperatures being sufficiently high to cause injury to the heat exchanger in the absence of cooling thereof, and a plurality of elements secured to said tube means and spaced on the tube means in the direction of flow of the high temperature fluid stream, each of said elements passing through a wall of the tube means and including oppositely extending portions respectively for projecting into said high temperature fluid stream and the other of said fluid streams, each of said elements having a predetermined ratio between the surface areas of said portion projecting into the other of said fluid streams and the portion projecting into the high temperature fluid stream, said ratio for certain of said elements located upstream of the high temperature fluid stream being greater than said ratio of other of said elements located downstream of the high temperature fluid stream so as to reduce any possibility of injury to the elements while promoting efficient operation of the heat exchanger.

2. A heat exchanger, as defined in claim 1, wherein said tube means is disposable transversely of said second mentioned stream, which second mentioned stream is the high temperature stream, a plurality of said spaced elements being arranged on said tube means with said ratio of the elements adjacent a leading edge of the tube means being greater than said ratio of the elements adjacent a trailing edge of the tube means.

3. A heat exchanger, as defined in claim 1, wherein said tube means includes a plurality of separate tubes disposable transversely of said second mentioned fluid stream which is the high temperature stream, each of said tubes having a plurality of said spaced elements arranged thereon with said ratio of elements adjacent leading edges thereof being greater than said ratio of elements adjacent trailing edges thereof.

4. A heat exchanger, as defined in claim 3, wherein said ratio of substantially all of said elements on a tube disposable downstream of said second stream from a preceding tube is less than said ratio of substantially all of the elements on said preceding tube.

5. A heat exchanger, as defined in claim 1, which includes additional elements similar to said first mentioned elements spaced along said tube means in the direction of flow of said other of said fluid streams, said ratio of certain of said additional elements located upstream of said other fluid stream being less than said ratio of other of said additional elements located downstream of said other fluid stream.

6. A heat exchanger comprising tube means for a first fluid stream which enters at a first temperature, said tube means being disposable in a second fluid stream which approaches a leading portion of the tube means at a relatively high temperature sufficient to cause injury to the heat exchanger in the absence of cooling thereof, and a plurality of elements secured to said tube means in the direction of flow of said first mentioned fluid stream, each of said elements passing through a wall of said tube means and including oppositely extending end portions respectively for projecting into said first mentioned fluid stream and said high temperature fluid stream, each of said elements having a predetermined ratio between surface areas of the end portions projecting into said first mentioned fluid stream and said high temperature fluid stream, said ratio for certain of said elements located upstream of said first mentioned fluid stream being less than said ratio of other of said elements located downstream of said first mentioned fluid stream so as to reduce any possibility of injury to the elements while promoting efficient operation of the heat exchanger.

7. A heat exchanger comprising a generally U-shaped tube for a first fluid stream which enters at a first temperature, said tube being disposable transversely in

a second fluid stream which approaches a leading edge of the tube at a different temperature, said tube having a substantially streamlined transverse cross sectional shape for promoting intimate contact of fluid in said second stream with the outer surface of said tube, one of said temperatures being sufficiently high to cause injury to the heat exchanger in absence of cooling thereof, and a plurality of pins secured to and spaced transversely of and longitudinally of said tube, each of said pins having inner and outer end portions respectively for projecting into said first and second mentioned fluid streams, each of said pins having a predetermined ratio between surface areas of its inner and outer end portions, said ratio of

pins disposed at various locations being varied in accordance with the temperatures of said first and second mentioned fluid streams at said locations so as to reduce any possibility of injury to the pins while promoting efficient operation of the heat exchanger.
